UNITED STATES PATENT OFFICE.

HAROLD T. AVERY, OF SAN LUIS OBISPO, CALIFORNIA.

AIRSHIP.

Application filed March 24, 1925. Serial No. 17,959.

This invention relates to improvements in airships so constructed that the weight of the airship is counterbalanced, in whole or in part, by the inflation of portions of the airship with some gas lighter than air. In an airship so constructed it is ordinarily necessary to have the ship's weight very accurately counterbalanced at times of landing and of "taking off", which usually involves much expense and time in accurately adjusting temperatures and inflations. Also in flying such an airship it sometimes happens that a high object lies in the path of the ship, which the ship has not sufficient buoyancy and climbing ability to surmount. In all of these instances it would be desirable to be able to exert a portion of the power of the airship's engines in a direction vertically upward, or vertically downward, and to move the ship upward or downward without its weight being accurately counterbalanced by inflation, and with limited horizontal motion, or no horizontal motion at all.

The general object of this invention is to provide an airship with such additional equipment or appurtenances as to make possible the objects outlined as being desirable in the last sentence above.

To this end it is proposed to equip the airship with certain additional propellers, arranged in such a manner as to make possible the attaining of these objects. Further objects of the invention will appear hereinafter.

The invention consists in the novel parts and combination of parts to be described hereinafter, all of which contribute to produce an airship which can be handled with greater ease, dispatch, accuracy, and economy than has heretofore been possible, particularly in landing, taking off, surmounting objects, and holding fixed positions in the air.

A preferred embodiment of the invention is described in the following specifications, while the broad scope of the invention is pointed out in the appended claims.

In the drawings;

Fig. 1 is a side elevation of one of the power cars of an airship, showing the additional propellers with which it is proposed to equip certain of the power cars.

Fig. 2 is a rear elevation of the same power car.

Fig. 3 is a plan of the same power car.

Fig. 4 is a side elevation of the engine and

certain of the machinery in the same power car (sectioned along line 4—4, Fig. 5), showing particularly the shafts, clutches, and gears which it is proposed to use in manipulating the propellers.

Fig. 5 is a rear elevation of the same machinery (sectioned along line 5—5, Fig. 4).

Fig. 6 is a plan of the same machinery shown in Figures 4 and 5.

Fig. 7 is a bow elevation of the airship showing the proposed arrangement of power cars and propellers.

Fig. 8 is a side elevation of the airship showing the same arrangement of cars and propellers.

Fig. 9 is a bottom plan of the airship showing the same arrangement of cars and propellers as Figures 7 and 8.

According to my invention, I provide, in addition to the propellers with which an airship is customarily equipped to propel it longitudinally, certain additional propellers mounted to revolve on vertical axes, and certain other additional propellers mounted to revolve on horizontal axes perpendicular to the length of the airship.

Figures 1, 2 and 3 show one of the power cars equipped with certain of these additional propellers. Propeller 1 is the propeller with which such a power car is ordinarily equipped to propel the airship longitudinally. In addition to this, I provide propeller 2, which is mounted to revolve on a vertical axis, and propeller 3, which is mounted to revolve on a horizontal axis perpendicular to the length of the airship.

Although there is no limit to the number of mechanical arrangements that could be devised, within the scope of this invention, for the driving of these propellers, I have represented in Figures 4, 5, and 6 one such possible arrangement.

Shafts 4, 5, and 6 are the shafts on which propellers 1, 2, and 3, respectively, are mounted. These are arranged to be driven selectively or in combination by engine 7. To allow of this I provide clutches 8, 9, and 10, and gears 17, 18, and 19. Although I have indicated clutches 8, 9, and 10 to be of the cone type, any suitable type of clutch can be used that will allow the operator, when desired, to disengage the clutch and thus leave the shaft on one side of the clutch free to revolve independently of that on the other side, or, when desired, to smoothly engage the clutch, thus making the

two pieces of shaft the equivalent of one continuous piece of shafting.

I provide on shaft 4, between clutches 8 and 9, a worm gear 11, having teeth set 5 at a sharp enough angle to freely drive the worms meshing with it. On the end of shaft 6 I provide a worm 12, meshing with gear 11. Thus whenever engine 7 is running and clutch 8 engaged, shaft 6 will be 10 driven by means of gear 11 and worm 12; and if clutch 10 is engaged propeller 3 will be driven, while if it is disengaged propeller 3 will be idle.

I provide, also, auxiliary shafts 13 and 15 14 on the upper ends of which are mounted worms 15 and 16, respectively, meshing with worm gear 11, and on the lower ends of which are mounted gears 17 and 18, respectively. Midway between the lower portions 20 of shafts 13 and 14 stands the upper portion of shaft 5. Gear 19 is keyed to shaft 5, but is arranged so that it can be slid along the shaft when desired. Thus when gear 19 is shifted down to mesh with gear 17, shaft 5 and propeller 2 will be connected for driving in one direction, while when it is shifted up to mesh with gear 18 they will be connected for driving in the opposite direction, and when in a position 30 not meshing with either they will be idle. The purpose of clutch 8 is to allow of disconnecting these gears from the engine, by disengaging the clutch, during the shifting of these gears.

When engine 7 is running and clutches 8 and 9 both engaged, propeller 1 will be driven by the engine. If it is desired to have this propeller idle during the use of one or both of the other propellers, clutch 9 40 may be disengaged.

Thus it is possible by the manipulation of clutches 9 and 10 and the shifting of gear 19, to drive off of engine 7 any one of the three propellers independently, driving propeller 2 in either direction desired, or to drive simultaneously any combination of two propellers, or all three at once.

Although there is no limit to the number of different arrangements of power cars and propellers that may be devised within the scope of this invention, I have represented in Figures 7, 8, and 9 my preferred embodiment of the general arrangement.

As shown in the above mentioned figures, 55 four of the power cars I provide are each equipped with three propellers, in the manner outlined above. Two power cars, 20 and 21, are arranged exactly like the power car shown in Figures 1, 2, and 3; and two power cars, 22 and 23, are similar to cars 20 and 21 except reversed side for side. These four power cars are placed so as to be located, in plan, at the four corners of a trapezoid, they being so located as to make the trapezoid as large and as nearly rectan-

gular as practicable, and to center as nearly as practicable the center of mass of the airship.

In addition to these four power cars, I provide two other power cars, 24 and 25, 70 located opposite each other at about the middle of length of the trapezoid mentioned above, each equipped with one reversible propeller revolving on a longitudinal axis, the entire machinery on these 75 power cars being similar to that on existing airships. All of these power cars are attached to the main body 26 of the airship, portions of which are arranged for inflation with gas lighter than air.

When it is desired to raise the airship, the vertical propeller 2 on each of the four power cars 20, 21, 22, and 23 can be driven in the proper direction for raising the airship; and when it is desired to lower the airship, driven in the opposite direction. The longitudinal motion of the airship during raising or lowering may be accurately controlled by the reversible propellers of power cars 24 and 25, or if it is desired to drive the ship forward at any considerable speed during either of these processes propellers 1, 1, 1, 1 on power cars 20, 21, 22, and 23 may be utilized.

If at any time it is desired to move the airship sidewise, or to offset the effect of a side wind against it, as might be particularly desirable when lowering the ship into some particular position, this may be accomplished by using propellers 3, 3 on power cars 20 and 21, or on power cars 22 and 23, depending on the direction of movement or force desired. If, similarly, it is desired to rotate the ship horizontally, this may be accomplished by using propellers 3, 3 on power cars 20 and 23, or on power cars 21 and 22, depending on the direction of rotation desired.

It is thus possible with an airship equipped as described, to use the majority of the power of the airship's engines to raise or lower the ship, at the same time keeping all horizontal motion and rotation of the ship entirely within control, so that the airship may be accurately raised or lowered to any desired position.

It is understood that the embodiment of the invention described herein is only one of the many embodiments this invention may take, and I do not wish to be limited in the practice of the invention, nor in the claims, to the particular embodiment set forth.

What I claim is:—

1. In an airship, the weight of which is counterbalanced, at least in part, by the inflation of portions of the airship with gas lighter than air, the combination of two power cars or units located opposite each other near the forward portion of the airship and two power cars or units located

opposite each other near the rear portion of the airship, each of the cars or units having one propeller designed to revolve on an axis approximately parallel to the length of the airship, and one propeller designed to revolve on an axis approximately vertical, and having means for driving said propellers, either together or separately.

2. In an airship, the weight of which is 10 counterbalanced, at least in part, by the inflation of portions of the airship with gas lighter than air, the combination of two power cars or units located opposite each other near the forward portion of the airship 15 and two power cars or units located opposite each other near the rear portion of the airship, each of the cars or units having three propellers, one designed to revolve on an axis approximately parallel to the 20 length of the airship, one designed to revolve on an axis approximately vertical, and one designed to revolve on an axis approximately horizontal and perpendicular to the length of the airship, and having means for 25 driving said propellers, either all together, in combinations as desired, or separately, allowing such propellers as desired to remain idle.

3. In an airship, the combination of two 30 power cars or units located opposite each other near the center of length of the airship having propellers mounted on axes parallel to the length of the airship, also two power cars or units located opposite 35 each other near the forward portion of the airship, and two power cars or units located opposite each other near the rear portion of

the airship each of the last mentioned cars or units having three propellers mounted on mutually perpendicular axes, and having 40 means for driving said propellers, either all together, in combinations as desired, or separately, allowing such propellers as desired to remain idle.

4. In an airship, the weight of which is 45 counterbalanced, at least in part, by the inflation of portions of the airship with gas lighter than air, the combination of two power cars or units located opposite each other near the center of length of the airship, having propellers designed to revolve on axes approximately parallel to the length of the airship and having means for driving and at will reversing the direction of rotation of said propellers, also two power 50 cars or units located opposite each other near the forward portion of the airship, and two power cars or units located opposite each other near the rear portion of the airship, each of the four last mentioned power 55 cars or units having three propellers, one designed to revolve on an axis approximately parallel to the length of the airship, one designed to revolve on an axis approximately vertical, and one designed to revolve on an axis approximately horizontal and perpendicular to the length of the airship, and having means for driving said propellers, either all together, in combinations as 60 desired, or separately, allowing such propellers as desired to remain idle.
